UNITED STATES PATENT OFFICE.

JOSEPH M. MCMASTER, OF ROCHESTER, NEW YORK.

GRAIN-BINDER.

SPECIFICATION forming part of Letters Patent No. 252,237, dated January 10, 1882.

Application filed March 23, 1881. (Model.)

To all whom it may concern:

Be it known that I, JOSEPH M. MCMASTER, of Rochester, Monroe county, New York, have invented certain new and useful Improvements 5 in Grain-Binders; and I do hereby declare that the following is a full, clear, and exact description of the same, reference being had to the accompanying drawings, in which—

Figure 1 is an elevation of the machine, looking on one side. Fig. 2 is an elevation, looking on the opposite side. Fig. 3 is a plan with the upper plate removed. Figs. 4, 5, 6, 7, 8, 9, 10, 11, and 12 are detail views. Figs. 13, 14, 15, and 16 are views of modifications.

My improvement relates to grain-binders in which a cord or string is used; and it consists in the construction and arrangement of parts hereinafter more fully described.

In the drawings, B represents a plate, which 20 I denominate the "body-plate," and which forms a part of the platform upon which the grain is received preparatory to binding. On the under side of the body-plate are two or more studs, *a a*, riveted to the plate and forming the bearings for a shaft, C, which turns freely therein. To this shaft are secured, by 25 means of keys or other suitable means, cams 3, 4, 5, and 6, by which the various parts of the mechanism are operated. To the bottom 30 of the studs *a a* is attached a plate, A, by which the operating parts are supported at the front end of the machine.

The looping device consists of the shaft D, fixedly attached in an angular or inclined position to a stationary bearing, E, said shaft being provided with a screw-thread, *b*, Fig. 9, and of an exterior collar, D', resting outside the shaft and having a pin, *c*, which engages with the threads. As the collar is turned in one 40 direction and the other it runs up and down on the screw.

F is a spindle passing loosely through the shaft D, having at its top a hook, *d*, for catching the cord and tying the knot, and having also pivoted to its side, near the top, a latch, *f*, which rests in a slot, *g*, of the shaft and operates to hold the cord while being looped, as will presently be described. The latch falls to a horizontal position and rests upon a shoulder, *h*, when the spindle is raised, and is drawn

into the tube with the spindle when the spindle is lowered.

i is a block secured on the upper end of collar D', having in its upper end a slot in which rests a spiral-spring guard-wire, *k*, attached at 55 its lower end to or within the block, its upper end making a full turn and a little more, and projecting beyond the block, as shown at *k'*. Behind the projecting end *k'*, and between it and the block, is a groove, *l*, which receives 60 the cord to carry it around in the act of looping, as will be hereinafter described. A prong, *j*, inside the projecting point *k'*, is used for catching and holding the cord more securely. This prong prevents the cord, when drawn vertically, from getting between the collar and screw. When the cord enters behind the spring end *k'* the latter yields outward, to allow the 65 cord to pass, and when the cord has once entered the spring end presses forward again, 70 holding the cord by its elasticity.

G is a double armed rock-lever, pivoted at *m*, with its arms *n n* extending on opposite sides of the machine, as shown in the plan view Fig. 3.

To the arms are attached chains H H, which extend to and wind upon the collar D' in reverse directions. As the lever is rocked backward and forward, it will be seen that the collar D' will be correspondingly turned forward 75 and back, and will correspondingly move up and down on the screw D, as before described. The shank *o* of the rock-lever extends back beyond the pivot *m*, so that as the shaft C is turned the rock-arm will be vibrated forward 80 and back by the reverse or alternate action of the cams 3 and 4, which strike the shank on opposite sides of the pivot *m*.

I is a vertical rock-shaft on one side of the machine, having its bearings in the two plates 85 B A. To the bottom of this shaft are rigidly attached two arms, K K, which turn with it, and to the top of the shaft is attached a third arm, L, which, however, is not rigidly attached to the shaft, but is attached to a hub, *p*, which 90 turns freely on the upper journaled end, *e*, of the shaft.

Fig. 4 is an elevation of the shaft and the arms, and Fig. 5 is a cross-section of the shaft and a plan of the lower arms, together with 100

the shear arrangement shown at the top of said figure. The outer ends of all three arms have V-shaped notches q , which receive the cord and carry it up to the binding apparatus. 70

5 When the arms move forward to catch and carry up the cord these notches all come in the same vertical line and move in the same position till the cord is carried to place.

The rock-shaft receives motion in reverse 10 directions by means of two angular pins, r and s , the first of which, r , is acted on by the cam 5 to throw the shaft one way, and the last, s , is acted on by a pin, t , attached to main shaft C, which strikes it to throw it in the other direction. 15 These movements are properly timed to throw the arms to bring the cord up to the looper and knotted.

To the hub p is attached a projecting arm, u , which engages with the cam 5, and to the 20 back of the arm L is attached a head, v , which engages with the cam 6. The cam 6, striking this head, forces the arm forward with the cord, while the cam 5, striking the arm u , which has been thrown across its path, forces 25 the hub and the arm L back again.

On the lower arm, K, are two fixed pins or 30 studs, w , standing upright at some distance apart, (Figs. 4 and 5), between which pins rests the long arm x of a shear-cutter, M, which is pivoted at the opposite end at y between two plates, N N, on the opposite side of the machine. The cutter has a head, z , which strikes closely between the plates, which at that point are somewhat notched, as shown in Fig. 5.

35 The upper edge of the cutter is sharp-edged, and the lower edge is rounded, Fig. 6, and the plates N N are correspondingly shaped, the upper plate being sharp-edged and the lower one rounded where the cutter fits. By this means 40 when the cutter is forced between the plates, with the cord resting over the same, the cord, when it passes between the plates, will have its upper length severed or cut by the sharp edge, while the lower length will be simply 45 pinched and held between the rounded edges. The length severed is that which passes around the bundle, while the length pinched and held is that which extends up and is connected with the binder-arm, and which, in that condition, 50 is ready for a new bundle. The arms K K are far enough apart to extend above and below the plates N N, and as they move up they carry the cord with them, and that part of the cord which extends from arm to arm is brought around 55 the head of the cutter, and the latter then carries it between the plates N N, as before described. The upper arm, L, also passes between the body-plate B and a plate, a^2 , on its under side, and the cord which is carried forward by this upper arm is also clamped and held for the time being firmly in place.

60 P is a clamp, consisting of two spring-arms, b^2 b^2 , separated at their outer ends, and which stand in line with but above the notched ends of the arms K K, and which, as the said arms carry the cord up, catch the length of cord be-

tween them and hold the same with a certain degree of tension, which, however, allows the cord to slip endwise when a given strain is reached. 75

In some of the figures of the drawings a single length of cord only is shown for convenience of illustration. The knotting devices are as effective on a doubled as upon a single length of cord. 80

To the bottom of the spindle F, which carries the hook and latch, is attached a horizontal arm, c^2 , Fig. 1, which connects at its opposite end with a vertical rod, R. The top of rod R is pivoted at d^2 to a rock-arm, S, the opposite end of which is pivoted at f^2 to a lug, g^2 , of the body-plate B. Under the rock-arm S rests a roller or pin, h^2 , attached to the upper end of an inclined rock-lever, T, which is pivoted centrally at i^2 to a hanger, k^2 , extending 85 down from the body-plate. Fig. 10 is a side view of this apparatus. The lower end of the rock-lever T projects inward, and is in position to be operated by the cam 5.

On one side of the rod R is a roller or stud, l^2 , which is acted upon by the stiff pin or crank-arm t , projecting from the main shaft C. The cam 5, striking the rock-lever T, causes the same to move the roller h^2 forward and raise the arm S, and consequently raise the spindle 90 F through the medium of the connections R c^2 . In the reverse action the pin t strikes on top of the roller l^2 on rod R and forces the spindle down again. The parts are properly timed to produce the desired effect. A spring, n^2 , is used, bearing under the rock-arm S, to assist in raising the same. 95

From the above description the operation will be readily understood. The end of the cord extending from a reel is pinched and held by the cutter-head, the cord being connected with a binder-arm which rises and falls in front of the three arms K K L. The binder-arm, passing up, leaves the length of cord behind. After the bundle has been gathered against 100 the cord the binder-arm descends, carrying the cord down on the opposite side of the bundle and to a point below the two lower arms, K K. The arms K K and L now move up to place, carrying the cord with them. The upper lengths 105 of the cord, which are tight around the bundle on top of the body-plate B, are pinched up tight by the arm L and held in that position with the tension on the bundle. The lower arms, K K, carry the cord between the clamps b^2 b^2 , and also up to the cutter, where it is carried between the plates N N, the upper length being cut off and the lower one pinched in place. The doubled ends of the cord holding the bundle are now free below, except the hold 110 they have in the clamps b^2 b^2 . The looper now begins its work. The cord is so laid that it comes in the groove between the spring-wire k^2 and the prong j , and also passes behind the projecting latch f . This latch holds the upper 115 part of the cord stationary. The collar D' now revolves, rising as it revolves, and the cord 120

resting in the groove is carried with it, making a loop, as shown in Fig. 7. When the loop is made the length of cord slips over the top of the shaft D, and is carried across under the hook, as shown in Fig. 8. The spindle F then draws down the hook, drawing the cord into the hollow shaft D and forming the knot, and the latch withdrawing to release the cord. While the cord is being looped the clamps b^2 5 hold the loose ends with sufficient tension to keep the cord straight; but the ends finally pull out and release the cord, when the operation is complete.

The hook is made sharp-edged on its under 15 side, as shown in Fig. 11, so as to cut the cord when the knot is drawn tight, and thus free the parts.

Various modifications may be used. In Fig. 13 the looping devices stand horizontally, and 20 a double-threaded instead of a single-threaded screw is used. The collar D' is also cogged on its outer surface, and with it engages a cog-rack which extends from arm to arm of the rock-lever, being used in place of the chains. 25 In Fig. 15 a flat spring with a bent end is used in place of the spring-wire k , and a projection at the side is used in place of the latch. In Fig. 16 the latch is shown pivoted to the shaft D instead of to the spindle F, and it is opened 30 and closed by the spindle as it runs up and down.

Having thus described my invention, what I claim as new, and desire to secure by Letters Patent, is—

35 1. In a grain-binder, the combination of the fixed screw-shaft D, the hollow collar D', engaging with the screw-shaft and provided at its top with the spring-wire k and prong j , and the spindle F, passing through the shaft 40 D, provided at its top with the hook d and on its side with the pivoted la'ch f , as shown and described, and for the purpose specified.

2. The combination, with the rock-shaft I, of the two arms K K, attached fast to the bottom of the shaft, and the single arm L, turning on the upper end, said arms having at their outer ends notches for catching the binding-cord and carrying it forward in position to be acted upon by the cutter-head and looping device, as herein shown and described. 45

3. The combination, with the arm L, having a hub which turns freely on the upper end of shaft I, of an arm, u , engaging with the cam 5, and the projecting head v , engaging with the cam 6, as shown and described, and for the purpose specified. 50

4. In combination with the arms K K, the cutter M, having a shank, x , which rests between pins $w w$, attached to the lower arm, and plates N N, between which the cutter is pivoted, 60 said cutter having a sharp cutting-edge at its top which engages with a corresponding sharp edge of the upper plate and a rounded edge at its bottom which engages with a rounded edge of the lower plate, as and for the purpose specified. 65

5. The combination, with the swinging arms K K L and looping apparatus D D', of the spring-clamps b^2 b^2 , arranged in the same concentric line with the notches or fingers at the outer ends of the swinging arms, for the purpose of catching and clamping the cord as it is carried forward by the arms, and holding it with sufficient tension while the cord is being looped, as herein shown and described. 70

In witness whereof I have hereunto signed my name in the presence of two subscribing witnesses. 75

JOSEPH M. McMaster.
